UNITED STATES PATENT OFFICE.

SAMUEL KAYE, OF COLUMBUS, MISSISSIPPI.

FEEDING MEANS FOR BOTTLE-CAPPING MACHINES.

1,280,487.

Specification of Letters Patent.

Patented Oct. 1, 1913.

Application filed July 22, 1912. Serial No. 852,673.

To all whom it may concern:

Be it known that I, SAMUEL KAYE, a citizen of the United States, residing at Columbus, in the county of Lowndes and State of Mississippi, have invented certain new and useful Improvements in Feeding Means for Bottle-Capping Machines, of which the following is a specification.

My invention relates to an improvement in apparatus for feeding crowns or caps to bottle-capping machinery.

The object is to provide a cap or crown feeder of large capacity, which will insure the proper positioning and presentation of the caps or crowns to the bottle-capping machine; to supply the latter as fast as they are required; and to insure against over-feed and clogging of the machine by providing relief for supernumerary caps or crowns, should the capacity of the bottle-capping mechanism be exceeded.

With the foregoing objects in view, my invention consists of a novel feed comprising an inclined feed-chute, a sorter, and a receiving-drum having an inlet in its side, the length of which approximately corresponds to the width of the inclined feed-chute. This drum and sorter revolve in connection with a stationary casing which partly surrounds them, which casing is surmounted on a suitable base or support, and which drum acts in conjunction with the inclined feed-chute to alternately receive and cut off the flow of caps from the chute into the drum, the caps at the lower end of the inclined chute bedding themselves against the drum, as the latter revolves, in position to fall through the inlet into the interior of the latter as the inlet rises to them and as the drum has capacity to receive them, or to be excluded if the capacity of the drum to receive them shall have reached its limit and they have reached a height in the drum to keep the inlet closed. From this receiving-drum the caps or crowns work their way over into the sorter which is of greater diameter than the drum, and in which they are tumbled about and finally received by suitable means, when presented in proper

position, preparatory to discharging them into the chute which supplies the bottle-capping machine.

In the accompanying drawings:

Figures 1 and 2 are views in elevation from opposite sides of the machine;

Fig. 3 is a plan view partly in horizontal section; and

Fig. 4 is a detail view in section showing some of the sorting lugs, in perspective.

The numeral 1 represents the receiving-drum, one end of which has a head 2 with an orifice 3 through the center which receives a sleeve 4. This sleeve has a flange 5 at one end by which it is secured to some stationary part of the machine. The shaft 6 extends through and is journaled in this sleeve 4 having a bevel-gear 7 at one end through which rotary motion is imparted to the shaft. The drum is provided with an inlet 8 in the form of an elongated slot in one side thereof, through which the caps C from an inclined feed-chute 9 are received as the drum turns and the inlet reaches the lower end of the inclined feed-chute, where the caps have been held by the revolving surface of the drum, until the inlet reaches and passes through the bed of caps formed between the lower end of the chute 9 and the surface of the drum, when the latter receives as many as flow in to replenish the drum. If, however, the drum has already been filled to a point where the inlet is covered, or nearly covered by the caps within the drum, the caps are then rejected until the level within the drum has sufficiently lowered to leave the inlet open sufficiently for the entrance of more caps, when the drum makes further complete revolutions.

The outer end of the receiving-drum is flared, as at 11, forming the inner end of the sorter S, and at the outer edge of this flared portion the undercut sorting lugs 12, 12, are radially arranged. A dished head 14 constitutes the outer member of the sorter S, and has a central hub to receive the outer end of the shaft 6 upon which it is removably held by any approved means, as for instance the spring-actuated pin 15. This head is circu-

lar in form, and is so constructed and its diameter is sufficient so that when in position it rests against the sorting-lugs and closes the outer sides of the latter, where it is secured to the flared portion 11 of the drum, so that the sorter and drum are to all intents and purposes a single member of the machine, although made in two parts secured together.

10 Beyond the lugs, the edge of the dished head 14 extends sufficiently far to form a channel 17 for the caps in cooperation with the flange 18 on the casing 16. This channel only extends part way around the periphery of the sorter, the filler 21 filling a portion of the channel, and the upper portion of the casing 16 of the machine being cut away, as shown in dotted lines in Fig. 2.

Within the sorter a number of pins or 20 similar devices 22, 22, are secured for the purpose of agitating the caps or crowns as they are tumbling about the sorter, to cause them to present themselves in the right position to pass between the sorting-lugs.

25 A hopper 10 is stationed above the inclined feed-chute 9 to supply the caps or crowns to the latter.

30 A brush 23 is located in position above the drum (as shown in Fig. 1) to brush back and prevent any caps which might happen to catch in the inlet 8 from passing on around with the drum.

The drum and sorter revolve in the direction of the arrow in Fig. 2. The caps are 35 received in their proper position where they have dropped by gravity between a number of sorting-lugs 12, 12, (as shown in Fig. 2), out of which they drop one by one into the channel 17 as the latter is reached, lining up 40 one above another preparatory to entering the chute 19 which leads to the capping-mechanism well-known but not shown.

Should the caps accumulate in the channel faster than they are taken by the capping-mechanism, and in any way become lodged or fastened to the caps between the sorting-lugs and moved upward, they always find escape over the edge of the cut-away portion of the casing 16 back to the 50 chute 9, where they are in time received again into the drum. This, however, does not generally occur, as the caps between the sorting lugs rarely ever disturb the caps in the channel but freely drop back into the 55 sorter when moving around the upper portion of the sorter.

From the foregoing, it will be understood that the feed-hopper 10 is adapted to afford a continuous supply to the inclined feed-chute, which rests at the bottom upon the traveling surface of the drum where the caps are in readiness to drop into the drum each time the inlet 8 returns with a revolution of the drum and sorter, (providing

the latter are not already filled to capacity) 65 in which event the drum automatically rejects any additional caps by reason of the caps within effecting a complete or partial closure of the inlet 8. So long as this occurs, no more caps are needed or received, 70 but when the level within decreases and the inlet is free to receive more caps, they descend from the chute through the inlet thereinto by gravity as the inlet passes through the bed of caps or crowns.

75 Thus the caps are fed into the drum and sorter automatically, and in this way an over-supply is impossible, and the level within the drum and sorter is maintained practically uniform and constant at all times, 80 so that neither cessation nor excess of feed is possible so long as the hopper 10 is supplying caps and crowns to the machine. The sorter meanwhile is doing its work with precision, always presenting as many or more 85 caps in proper position as the channel 17 can accommodate, and the sorter receiving back the oversupply of caps when the channel happens to be crowded or full above a certain point.

90 From the foregoing it will be seen that I have provided a machine of unusually large capacity, which takes the caps as they are required, positions them, and keeps the capping-machine fed continuously, as fast as 95 there is a demand for the caps or crowns.

I claim:—

1. A feeding means for bottle-capping machines comprising a feed-chute, a casing, and a combined hollow drum and sorter, the drum fitting and rotating in the casing, and closing the lower end of the chute, and having an inlet which is periodically presented by the rotation of the drum to the lower end of the chute to admit an intermittent and indeterminate supply of caps therefrom into the drum, after which, with the further rotation of the drum, the chute is closed by the drum while the inlet is closed by the casing until it again reaches the lower end of the chute.

2. A feeding means for bottle-capping machines comprising a feed-chute, a casing, a hollow drum rotatably mounted in said casing, and having an orifice in the side thereof, said casing being open above the chute, and means on the casing for brushing excess caps from the surface of the drum back toward the chute.

3. Feeding means for bottle capping machines comprising a chute, a casing, and a combined drum and sorter, the drum hollow and cylindrical and fitted to turn in the casing, and provided with an inlet, the sorter located at one end of the drum, in communication therewith and of greater diameter than the drum, the drum having an inlet for the caps which intermittently presents

itself at the lower end of the chute whereby the drum is fed, the cylindrical portion of the drum thereafter closing the chute while the caps are moving into and arranging 5 themselves by gravity in the sorter after which the inlet re-presents itself at the lower end of the chute to admit additional caps into the drum, which caps are again sorted

as the supply of caps is cut off by the body of the drum at the lower end of the chute. 10

In testimony whereof I affix my signature, in the presence of two witnesses.

SAMUEL KAYE.
